WEIGHING, BLENDING, ELEVATING, AND
SIFTING MACHINE

Frank X. Lauterbur and Edward J. Lauterbur,
Sidney, Ohio; Wilhelmina S. Lauterbur and Leo
V. Lauterbur executors of said Frank X. Lauter-
bur, deceased

Application January 2, 1929, Serial No. 329,739

6 Claims. (Cl. 249—16)

Our invention relates to weighing, blending, elevating and sifting machines in which there is such a coordination of operation and correlation of parts that the entire assembly may be mounted on a scale and batches of blended and sifted material, such as flour, may be dispensed or discharged, for example, into a dough mixer, without interfering with continuity of the operation of the mechanism and with great accuracy.

10 In the United States Patent No. 1,434,618 of Frank X. Lauterbur, there is described a machine for weighing, blending, elevating and sifting flour, which, in the particular modification illustrated, has a motor drive mounted independently of the mechanism, but so flexibly connected therewith as to permit weighing of discharged batches without binding the scale. Our present invention relates to improvements in the structure and in the principle of operation of the invention broadly disclosed in the aforesaid patent.

15 It is the object of our invention to combine the various mechanical parts required for blending, elevating, sifting and discharging as a unitary structure, preferably also including the motor drive therefor on a scale. It is our object to provide a scale which will be more readily accessible for setting than such scales have heretofore, to the best of our knowledge and belief, been, 20 and in which the amount to be discharged may be controlled by a setting on a beam or beams in a direct reading without the necessity of subtracting to determine the net weight to be dispensed.

25 It is further our object to provide a combination which, due to its construction, may be used with parts of the mechanism on one floor and other parts on another floor, so that the combination will more readily adapt itself for convenient and economical installation. It is further an object to provide a combination which will readily adapt itself to the positioning of the parts in different relative positions, one group of mechanism being adapted to be mounted either directly below or directly opposite another group of mechanism.

30 It is finally our object to provide an automatic electrical control for the mechanism which will become effective at the end of the weighing operation so that an operator may busy himself with other work without waiting to shut the machine off after a batch has been dispensed.

35 The above and other objects to which reference will be made in the ensuing disclosure I accomplish by that certain combination and ar-

angement of parts of which I have shown a preferred embodiment.

Referring to the drawings:—

Figure 1 is a side elevation of the machine all assembled on one floor.

Figure 2 is an end elevation of the machine shown in Figure 1.

Figure 3 is an end elevation of the weighing apparatus on an enlarged scale, the combination of parts being the same as that shown in Figures 1 and 2.

Figure 4 is a detail view showing the upper conveyor or sifter shown in the combination illustrated in Figures 1 and 2.

Figure 5 is a detail view showing the blender and weighing apparatus shown in Figures 1 and 2 on an enlarged scale.

Figure 6 shows a combination in which the blender and sifter is on one floor while the weighing beams and dough mixer are installed on the floor below.

Figure 7 is an end elevation of the combination shown in Figure 6.

Figure 8 shows another combination in which the dough mixer and sifter are mounted on the floor above the scales and blender, the weighing beams in this instance also being on the upper floor.

Figure 9 is a fragmentary elevation of the blending bin with the means for releasing to weighing position.

Figure 10 is a side elevation of the blending bin showing the supports in weighing position.

Referring first to the combination illustrated in Figures 1-5, we have shown the blending bin 1 having therein a rotatable shaft 2 which carries spiral ribbon-like agitators 3. The ribbon-like agitators are so arranged that material from within the bin 1 is fed toward the right as indicated in Figure 5, where it is received in a hopper or pocket 6. At the top of the bin 1, I have provided hinged drop doors 1a as indicated by the dot and dash lines. These drop doors are the inlet openings for the materials put into the bin. Sprocket wheels 7 encased in an upright casing 8 are mounted on the shaft 2 which carry the endless chain supports 1a for a bucket conveyor having buckets 8a which pick up the flour and deliver it through a head casing 9 into a discharging hopper 10. The discharging hopper has a spiral conveyor 11 therein which is mounted on a shaft 12 driven by a large gear 13 which is engaged by the pinion 14 of an electric motor 15. The shaft 12 is connected through gearing 16.

to means which engage and drive the chain supports of the bucket conveyor 16.

The spiral conveyor 11 feeds the flour which it picks up from the bucket conveyor or elevator 5 into a sifting head 17. The shaft 12 extends through the sifting head and has a brush type agitator 18 loosely mounted thereon. The clutch bearings 19 which are loose on the shaft support the brush agitator. A clutch collar 20 is keyed 10 on the shaft 12, and engages a clutch bearing which is mounted on the hub of the agitator 18. This permits the hub and agitator to be removed from the shaft when it is desired to remove the agitator through the end of the head. 15 A tie rod 21 extends from the head casing 9 to the head 17 to brace the assembly. A cylindrical screen 22 is also mounted in the sifting head through which the sifted flour will pass into the delivery chute 23 which has a telescopic connection 24 with the dough mixer which is generally illustrated at 25.

We have also shown the liquid tempering tank 26, as set forth in United States Patent No. 1,657,264, associated with the dough mixer 25 25 but inasmuch as neither the dough mixer or the blending tank, because of their particular structure, are included in the combination disclosed herein, no further description is thought to be required of their internal or operative construction. 30

The blending hopper and elevator casing and sifting mechanism, including the electric motor for driving same, are mounted on tie beams 27, it being understood that the telescopic joint of 35 the discharge chute will allow the entire assembly to be weighed as a unit.

The weighing apparatus, with the exception of the beam, is of usual construction. A drop handle 28 is connected by the link 29 to the drop arm 30, fixed on one of two shafts 31 mounted in the drop brackets 32; the two shafts 31 being connected by link 31a to rotate in unison. When the handle 28 is shifted the cams 32a which are fixed on the respective shafts 31 are released, 40 thereby permitting the tie beams to rest on the bearing pins 32b. The suspension links 35 then transmit the suspended weight of the mechanism to the arms 33, which are suspended by knives 34 from the suspension links 36. The suspension 45 links 36 are pivotally mounted on the suspension pins 37 carried by the suspension brackets 38. The suspension brackets are fastened to the base frame. Through the lever 39 and stirrup 40 and clevis 41 the suspended weight is transferred to 50 the hook rod 42 which is attached to the short arm of the weighing scale beam 43. The movement of the beam is regulated by a connection 44 with a dash pot 45 and it will be noted that in the modification illustrated in Figure 3, when the 55 dash pot is pulled up, it engages and holds closed a cut-out switch 46 which, through electrical connections 15a and 15b, is connected in the power feed lines to the driving motor 15, as shown by the wiring diagram in Figure 3.

60 The scale beam consists of a lower or weighing beam 47 which it will be noted has gradations extending in increasing gradations from the pivoted end of the beam toward the free end. The weighing beam is traversed by the poise 48. The beam has three arms, the upper and middle arms 49 and 50 respectively having gradations in increasing amounts extending from the free to the pivoted end. The upper beams are for weighing out the material to be dispensed, and are traversed by the poises 51 and 52 respectively. The

beam is further provided with an adjustment weight 53 which functions in the usual manner.

In the combination shown in Figures 6 and 7, it will be noted that the blender and sifter are incorporated in a single continuous hopper 54 5 having a sifting head 17a and a discharge chute 23a into a dough mixer 25 located on the floor below. The weighing apparatus is mounted underneath the mechanism on the upper floor, but the connecting rod 42 extends down through an 10 opening in the floor to the scale beam 43 which is mounted on the same floor as the mixer. There is a shifting rod 28 for the weighing apparatus on the upper floor so that an operator may balance his scale on the lower floor and make 15 his settings for the amount he is to discharge and then release the shifting rod on the upper floor. In some installations such an arrangement is advantageous, although as indicated, we prefer to provide an auxiliary shifting rod 28a 20 on the lower floor so that the operator may throw his apparatus into weighing position from either floor.

In Figure 8 a still different combination is disclosed. In this combination the blender 1 is arranged on a weighing platform on a lower floor and the hook rod 42 extended up through an opening in the floor to the weighing beams 48 located on the floor above. On the floor above are mounted the hopper and the sifting head. 30 The dough mixer is also located on the upper floor. The combination thus provided will be found to be very economical of floor space as both the blending hopper and the mixing bowl can be arranged substantially one below the other. 35

Modifications in the particular mechanism described will readily occur to those skilled in the art, but insofar as such modifications have incorporated therein the inventive principle involved, we consider them within the scope of our invention. 40

The operation of the mechanism will be apparent. The operator weighs gross the weight of the material on the beam 47, the gross weight 45 of the apparatus being ordinarily balanced by auxiliary weights. He then sets the poises on the beams 49 and 50. During the balancing of the beam 47 the cut-out switch 46 is closed. The operator then closes another switch 46a in the 50 motor circuit, as shown in Figure 3, and the apparatus is thus started up. As soon as the amount of material to be discharged, as predetermined by the direct weight settings of beams 49 and 50, has been dispensed, the composite 55 beam drops at its free end, thereby opening the switch 46 and shutting down the driving motor. The switch 46 is so positioned on the suspended apparatus that it is up out of range of the dash pot 45 and cannot be closed until the lever 28 is 60 thrown and the apparatus is lowered into balancing position. This prevents the operation of the apparatus except when it is properly set for weighing. 65

While we have discussed the apparatus described in connection with the weighing out of flour, it will be apparent that any dispensing apparatus such as might be used for dispensing a predetermined weight of material in pellet or granular form, might be mounted on a scale of 70 similar construction and an electrical control such as is described provided therefor.

Having thus described our invention, what we claim as new and desire to secure by Letters Patent, is:—

1. In combination, a beam scale having conveying and sifting mechanism carried entirely thereon, said scale having a composite scale beam with gross weight graduations reading from the pivoted end of the beam to the free end, and net weight graduations reading from the free end of the beam to the pivoted end, a motor for driving said apparatus also carried by said scale, and means for inhibiting the operation of said motor effective by said scale beam. 5
2. In a device of the character specified, in combination with a scale mechanism comprising a bin, a rotary sifter mechanism, a conveyor extending between said bin and sifter mechanism, means for mounting said mechanism on said scale, and means for also mounting a motor for driving said mechanism on said scale, said scale having a composite beam comprising gross beam or beams which is adapted to weigh the several devices mounted on said scale plus the contents thereof, and a net beam or beams which is adapted to weigh a net quantity to be dispensed. 10
3. In combination with a scale on which apparatus comprising a bin for excess material, a conveyor and an electric motor for driving same are mounted, means for weighing out a net weight in a direct reading from said excess material, and means for automatically cutting off said motor at the end of a weighing out operation comprising a cut-out switch in the power circuit to said motor, and means for moving said apparatus into and out of position to be carried by said scale, said cut-out switch being so positioned on said apparatus relative to said scale as to keep said circuit broken excepting when said scale has said apparatus carried thereon. 15
4. In a weighing and dispensing machine, a scale comprising means whereby it may be adjusted to have a movement upon removal of a desired weight of material therefrom, mechanism carried by said scale, operative to remove material therefrom, means controlling the operation of said mechanism and actuated incident to said movement of the scale to stop the operation of said mechanism, and means operative to prevent or permit said movement of the scale, actuating said controlling means to prevent operation of said mechanism upon operation to prevent said movement of the scale. 20
5. In a machine of the character described, a scale, means on said scale for holding material, means on said scale for discharging material from said holding means, an elevator extending up from said discharging means and also being supported on said scale, a conveyor extending laterally from the upper part of said elevator to discharge to receiving means displaced laterally from the scale, and mechanism for driving said discharging means, said elevator and said conveyor, also mounted entirely on said scale, said scale comprising a beam with a plurality of 10 poises and series of graduations for the respective poises to indicate their adjustments, one to weigh the contents of the holding means plus the weight of the structure on the scale, and the other to weigh an amount discharged from the holding means, up through the elevator and out through the conveyor, and means whereby the scale acts, upon discharge of the amount weighed by said other poise, to stop operation of the discharging means. 25
6. In a machine of the character described, a scale and material holding and discharging structure supported by the scale, said scale comprising levers fulcrumed at respective remote locations along the extension of the holding structure and supportingly engaging said structure substantially near their respective fulcrums, and a beam connecting with said levers and provided with means for indicating the weight imposed on the scale and transmitted through said levers, said machine also comprising means for manually relieving the scale levers and beam of the weight of the structure and contents of the scale, the discharging structure including a motor for actuating it, said machine also comprising operatively connecting means whereby the movement of the beam that connects the levers effects stoppage of the motor, and the means for indicating the weight on the scale including means preventing motor-stopping movement of said beam until a predetermined amount of material has been removed from the holding means, to a place where the removed material is no longer supported by the scale beam and levers, said operatively connecting means comprising 30 elements displaced from coacting relation incident to the relief of the scale levers and beam of the weight, to prevent operation of the motor unless the scale is in weighing condition. 35

FRANK X. LAUTERBUR. 50
EDWARD J. LAUTERBUR.
